UNITED STATES PATENT OFFICE.

THOMAS P. HARRIS, OF CLARINDA, IOWA.

RADIATOR PROTECTOR.

Application filed January 5, 1924. Serial No. 634,594.

To all whom it may concern:

Be it known that I, THOMAS P. HARRIS, a citizen of the United States, and a resident of Clarinda, in the county of Page and State of Iowa, have invented a certain new and useful Radiator Protector, of which the following is a specification.

The object of my invention is to provide a simple, durable and inexpensive radiator protector device designed to be readily, quickly and easily applied to a radiator without the use of tools of any kind, and when so applied it will form an insulator to protect the lower portion of a radiator from the direct impact of the air during excessively low temperatures.

A further object is to provide device of this character which, when applied, will be securely but yieldably held in position to prevent vibration relative to the automobile radiator or frame, and which will prevent any marring of the finish of the radiator frame when in use.

My invention consists in the construction of the protector and in the arrangement and combination thereof with an automobile frame and radiator, whereby the objects contemplated are attained, as hereinafter more fully set forth, pointed out in my claims, and illustrated in the accompanying drawings, in which:

Figure 1 shows a front elevation of a portion of an automobile frame and radiator with my improved protector applied thereto as in use.

Figure 2 shows an enlarged sectional view on the line 2—2 of Figure 1: and

Figure 3 shows a detail front elevation of a portion of the automobile frame cross pieces directly below the radiator and forming a support for the crank bracket.

Referring to the accompanying drawings my improved radiator protector comprises a body portion 10 preferably formed of fiber board having a slight degree of resiliency or flexibility. Its top and side edges are arranged on lines at right angles to each other, and its bottom edge is inclined from the sides downwardly and toward the center and at the center there is an upwardly extending notch with curved shoulders at 11.

At the top edge of the body portion 10 there is a metal reinforcing binder 12, and at the side edges are metal reinforcing binders 13 which extend from near the top edge downwardly to a point spaced apart from

the lower edge as hereinafter more fully set forth.

Attached to the body portion 10 at points spaced a substantial distance above the lower edge, and at points spaced on opposite sides of the vertical central line, are two spring clips, each of which comprises an anchoring portion 14 extended through the body portion 10, then upwardly and along the rear face thereof, then again forwardly through the body portion 10 and then downwardly across the front face of the body portion to rigidly anchor the clip to the body portion 10. Below this anchoring portion is the holding portion 15 which extends downwardly and rearwardly at 16, and then again downwardly and forwardly at 17.

The parts of the automobile with which my device is associated comprise a radiator 18, a radiator frame 19, which latter comprises a bar 20 extended across the lower portion of the radiator frame. This bar 20, in some kinds of automobiles, for instance the Ford automobile, is connected to the frame 19 only at its ends and its central portion is free to swing forwardly and rearwardly a slight distance relative to the front face of the radiator.

Below the radiator frame there is a cross piece 21 of the automobile frame, and at the central portion thereof there is a bracket 22 secured thereto and in which the crank 23 is supported. This bracket 22 extends downwardly across the face of the cross piece 21 and projects a slight distance in front of it, and at the ends of the cross piece 21 there are the ends 24 of other parts of the frame which usually overlap the front of the part 21 and are connected thereto by rivets 25, the heads of which project some distance in front of the cross piece 21. This cross piece 21 is spaced a substantial distance below the bottom member 20 of the radiator frame, and the front edge of the bracket 22 and the front edges of the rivets 25 and frame members 24 project slightly in front of a vertical line at the front face of the radiator, as shown in Figure 2.

In applying my improved protector to a radiator I place it flat against the front face of the radiator and then slide it down between the front of the radiator and the cross member 20 at the lower part of the radiator frame. If necessary this cross member 20 may be easily sprung forwardly a slight distance to permit downward movement of the

protector. This downward movement is continued until the spring clips 15 engage the cross member 20 and moved to the position shown in Figure 2, with the part 16 below 5 the cross member 20. During this movement the rounded edges 11 at the bottom edge of the protector will have engaged the crank 23, and the crank will then enter the slot at the bottom of the protector and loosely engage the sides of the slot.

During this downward movement of the protector, its lower edge will engage the bracket 22 and be forced slightly forwardly, and at the same time the side lower edges 15 of the protector will engage the rounded heads of the rivets 25 and be projected slightly forwardly, although not as much as the central portion of the protector. By thus extending the lower edge of the flexible 20 and resilient fiber board slightly forwardly, the cross member 20 serves as a fulcrum and tends to firmly hold the upper portion of the protector against the front of the radiator, thereby preventing vibration of the 25 protector relative to the other parts with which it is in contact.

By having the top edge and portions of the side edges of the protector reinforced with metal binders, the upper portion of the 30 protector is prevented from warping or sagging forwardly. However, the side edge metal binders extend only to a point above the cross member 20, thus leaving that portion of the protector below a line above the cross piece 21 flexible and resilient and not made rigid by the metal binder.

The metal binders 13 are held against contact at any time with the radiator frame 40 and the entire protector is held against lateral movement by the slot at the lower end of the protector engaging the sides of the frame, and the spring clips prevent all up and down movement of the radiator protector when it is once applied.

In practical use the radiator protector may be firmly and permanently attached in position for operation by simply placing it against the front of the radiator and pushing it downwardly and it may be detached by simply grasping its front edge and pulling it upwardly, and no tools are required or time lost in either attaching or detaching the protector.

In protectors of this character that contemplate covering the entire front of the radiator, it is always necessary and desirable to provide some means for ventilation for the upper half or more of the radiator. Experience has shown that after an automobile has been run for a very few minutes, it is not advantageous, even in extremely low temperatures, to cover all of the radiator front, and in practice I have found that with my improved protector covering only the lower half or less of the radiator front, it

produces the desired effect with a maximum of efficiency and convenience for the operator. With radiator protectors that cover only the lower half of the radiator, there are frequently conditions which make it 70 desirable to utilize the entire front of the radiator for radiating purposes. Hence, it is essential that at times the entire protector be removed, and where complicated attaching devices are employed, the driver of the 75 car is likely to neglect to remove the protector when conditions demand it, and thus injure the automobile; whereas with my improved device when the engine shows any 80 sign of heating, the protector may be readily, quickly and easily removed without tools.

I claim as my invention:

1. A radiator protector comprising a body portion made of resilient yielding material 85 such as fiber board shaped to rest against the front of the lower portion of the radiator and between the sides of the radiator frame and to extend downwardly between the lower member of the radiator frame and the front of the radiator to a point spaced a material distance below the lower member of the radiator frame and to engage and rest upon portions of the automobile frame below the radiator and slightly in front of 90 a vertical line at the front of the radiator, spring clip devices attached to the body portion and designed to engage the lower member of the radiator frame, whereby the 95 radiator protector may be attached to a radiator by placing it against the front of the radiator and moving it downwardly until the clips engage the said cross member 100 of the radiator frame, and during such downward movement the lower edge portion of the protector will be sprung forwardly to engage the portions of the automobile frame that are in front of the radiator to thereby cause the lower radiator frame member 105 to serve as a fulcrum to hold the upper end of the protector against the radiator.

2. A radiator protector comprising a body portion made of resilient yielding material such as fiber board shaped to rest against the front of the lower portion of the radiator and between the sides of the radiator frame and to extend downwardly between the lower member of the radiator frame and the front of the radiator to a point spaced a material distance below the lower member of the radiator frame and to engage and rest upon portions of the automobile frame below the radiator and slightly in front of a vertical line at the front of the radiator, spring clip devices attached to the body portion and designed to engage the lower member of the radiator frame, whereby the radiator protector may be attached to a radiator by placing it against the front of the radiator and moving it downwardly 110 115 120 125 130

until the clips engage the said cross member of the radiator frame, and during such downward movement the lower edge portion of the protector will be sprung forwardly to engage the portions of the automobile frame that are in front of the radiator to thereby cause the lower radiator frame member to serve as a fulcrum to hold

the upper end of the protector against the radiator, and reinforcing metal binders applied to the side edges of the protector and extending from a point above the lower cross member of the radiator frame to a point adjacent to the top edge thereof. 10

Des Moines, Iowa, December 5, 1923.

THOMAS P. HARRIS.
